CLAIM

I claim the ornamental design for a swimming accessory for hand, as shown and described.

DESCRIPTION

FIG. 1 is a perspective view of a swimming accessory for hand showing my new design with a section of the wrist strap shown in partially raised condition;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof; and,

FIG. 7 is a rear elevational view thereof.
